(57) **CLAIM**

The ornamental design for an inverted-model-vehicles-outfitted ceiling fan, as shown and described.

DESCRIPTION

FIG. 1 of the drawings is a perspective view of a inverted-model-vehicles-outfitted ceiling fan embodying the design of my invention, showing the bottom and side as viewed toward the space between any two adjacent fan blades; FIG. 2 is a side elevation view of the ceiling fan as viewed directly at any one of the fan blades, shown in its environment;

FIG. 3 is a bottom plan view of the inverted-model-vehicles-outfitted ceiling fan; and,

FIG. 4 is a top plan view of the inverted-model-vehicles-outfitted ceiling fan.

The broken line showing of environmental structure in FIG. 2 is for illustrative purposes only and forms no part of the claimed design.
